(57) **ABSTRACT**

A printer includes a printer body, a lid, a lock, a lock lever, and an open lever. The lid is attached to the printer body to be opened and closed. The lock locks a platen roller attached to one of the printer body and the lid. The lock lever unlocks the locked platen roller. The open lever is so provided on the lid as to slide. The open lever slides to press the lock lever to open the lid.

PRINTER

TECHNICAL FIELD

The present invention relates to printers.

BACKGROUND ART

Printers are widely used for shop registers and automated teller machines (ATMs) or cash dispensers (CDs) in banks. Printers that output receipts perform printing on recording paper with a head while conveying the recording paper, and after conveying the recording paper to a predetermined length, cuts the recording paper with a cutter. The cutter includes a fixed blade and a movable blade, and the movable blade slides toward the fixed blade to cut the recording paper between the fixed blade and the movable blade.

Furthermore, printers that include a printer body and a lid pivotably supported on the printer body to be opened to allow a roll of recording paper to be loaded in the printer body are known. In this case, for example, a head is provided in the printer body, and a platen roller is provided on the lid. By closing the lid, the recording paper is held between the head and the platen roller. Printing is performed on the recording paper with the head with the recording paper held between the head and the platen roller. The lid is provided with a lid opening lever for opening and closing the lid, and the lid can be opened by operating the lid opening lever.

PRIOR ART DOCUMENTS

[Patent Document 2] Japanese Laid-Open Patent

[Patent Document 3] Japanese Laid-Open Patent Application No. 2003-246104

SUMMARY OF THE INVENTION

Problems to be Solved by the Invention

According to the above-described printers, the lid, which is opened and closed at the time of loading a roll of recording paper, is provided with a spring that urges the lid in a direction to open at the connection between the printer body and the lid for a smooth opening operation of the lid.

There is, however, a general demand for low-cost printers, and printers reduced in the number of components without a spring or the like are preferred.

Furthermore, when cutting recording paper, the movable blade slides toward the fixed blade to cut the recording paper, but if the recording paper is held between the fixed blade and the movable blade sliding toward the fixed blade, the recording paper stuck between the fixed blade and the movable blade may prevent the movable blade from moving, thus preventing the movable blade from returning to its original state. In this state, the immobilized movable blade hinders the lid from being opened.

Means for Solving the Problems

According to an aspect of the present invention, a printer includes a printer body, a lid, a lock, a lock lever, and an open lever. The lid is attached to the printer body to be opened and closed. The lock locks a platen roller attached to one of the printer body and the lid. The lock lever unlocks

2

the locked platen roller. The open lever is so provided on the lid as to slide. The open lever slides to press the lock lever to open the lid.

According to an aspect of the present invention, a printer includes a printer body, a lid, a lock lever, and an open lever. The lid is attached to the printer body to be opened and closed. The lock lever separates a platen roller attached to one of the lid and the printer body and a recording head attached to the other of the lid and the printer body. The lock lever is provided in the printer body. The open lever is slidably attached to the lid and slides to operate the lock lever. The open lever is removable from the lid.

According to an aspect of the present invention, a printer includes a printer body, a lid, a lock lever, and an open lever. The lid is attached to the printer body to be opened and closed. The lock lever locks the lid to the printer body. The open lever is slidably attached to the lid and slides to operate the lock lever to unlock the lid. The open lever is removable from the lid.

Effects of the Invention

According to an aspect of the present invention, it is possible to reduce the cost of a printer in which recording paper is loadable.

Furthermore, according to an aspect of the present invention, it is possible to easily open a lid even with recording paper being stuck between a fixed blade and a movable blade slid toward the fixed blade in a printer.

BRIEF DESCRIPTION OF THE DRAWINGS

FIG. 1 is a perspective view of a printer according to an embodiment with a lid open.

FIG. 2 is a perspective view of the printer according to the embodiment with the lid closed.

FIG. 3 is a cross-sectional view of the printer according to the embodiment with the lid closed.

FIG. 4 is a side view of the printer according to the embodiment for illustrating a method of opening the lid.

FIG. 5 is a cross-sectional view of the printer according to the embodiment for illustrating the method of opening the lid.

FIG. 6 is a perspective view of the printer according to the embodiment for illustrating the method of opening the lid.

FIG. 7 is a side view of the printer according to the embodiment for illustrating the method of opening the lid.

FIG. 8 is a cross-sectional view of the printer according to the embodiment for illustrating the method of opening the lid.

FIG. 9 is a perspective view of the printer according to the embodiment for illustrating the method of opening the lid.

FIG. 10 is a side view of the printer according to the embodiment for illustrating the method of opening the lid.

FIG. 11 is a cross-sectional view of the printer according to the embodiment for illustrating the method of opening the lid.

FIG. 12 is a perspective view of the printer according to the embodiment for illustrating the method of opening the lid.

FIG. 13 is a side view of the printer according to the embodiment for illustrating the method of opening the lid.

FIG. 14 is a cross-sectional view of the printer according to the embodiment for illustrating the method of opening the lid.

FIG. 15 is a diagram illustrating the cutting of recording paper with a fixed blade and a movable blade.

FIG. 16 is a diagram illustrating the cutting of recording paper with the fixed blade and the movable blade.

FIG. 17 is a diagram illustrating the cutting of recording paper with the fixed blade and the movable blade.

FIG. 18 is a diagram illustrating the cutting of recording paper with the fixed blade and the movable blade.

FIG. 19 is a perspective view of the printer according to the embodiment where an open lever is removed and the lid is closed.

FIG. 20 is a diagram illustrating a method of opening and closing the lid of the printer according to the embodiment, depicting a state before removal of the open lever from the printer.

FIG. 21 is a diagram illustrating the method of opening and closing the lid of the printer according to the embodiment from which the open lever is removed.

FIG. 22 is a diagram illustrating the method of opening and closing the lid of the printer according to the embodiment from which the open lever is removed.

FIG. 23 is a diagram illustrating the method of opening and closing the lid of the printer according to the embodiment from which the open lever is removed.

FIG. 24 is a diagram illustrating the method of opening and closing the lid of the printer according to the embodiment from which the open lever is removed.

FIG. 25 is a perspective view of the printer according to the embodiment with the open lever removed and the lid open.

FIG. 26 is a diagram illustrating a structure of the open lever according to the embodiment.

FIG. 27 illustrates perspective views of the open lever according to the embodiment.

FIG. 28 illustrates perspective views of the open lever according to the embodiment.

FIG. 29 is a diagram illustrating the open lever according to the embodiment.

FIG. 30 is a diagram illustrating the open lever according to the embodiment.

FIG. 31 is a diagram illustrating the open lever according to the embodiment.

FIG. 32 is a diagram illustrating a method of operating a lock lever using the open lever according to the embodiment.

FIG. 33 is a diagram illustrating the method of operating the lock lever using the open lever according to the embodiment.

EMBODIMENT(S) OF THE INVENTION

An embodiment of the present invention is described below. The same member or the like is referred to using the same reference numeral, and a repetitive description thereof is omitted.

A printer according to this embodiment is described with reference to FIGS. 1 through 3. FIG. 1 is a perspective view of the printer with a lid open. FIG. 2 is a perspective view of the printer with the lid closed. FIG. 3 is a cross-sectional view of the printer with the lid closed.

The printer according to this embodiment includes a printer body 10 and a lid 20 attached to the printer body 10. The lid 20 is attached to the printer body 10 to be pivotable about a shaft. In other words, the printer according to this embodiment includes the lid 20 that is attached to the printer body 10 to be openable and closable. The printer body 10 includes a body case (recording paper holder) 11, and a roll of recording paper 100 is loadable in the body case 11. The

roll of recording paper 100 used in the printer according to this embodiment is thermal paper.

A control circuit board 12, motors 13 and 14, a thermal head 30, which is a recording head for printing on the recording paper 100, and a fixed blade 41 are provided in the printer body 10. The control circuit board 12 is for controlling the printer. Each of the motors 13 and 14 is for conveying the recording paper 100 or driving a movable blade 42 described below. One of the motors 13 and 14 may be used for conveying the recording paper 100 and the other may be used for driving the movable blade 42.

An open lever 21 for opening the lid 20, the movable blade 42, and a platen roller 50 are provided on the lid 20. The open lever 21 is provided to move upward and downward in a groove 22 provided in a front surface, that is, an exterior surface, of the lid 20.

According to this embodiment, the fixed blade 41 provided in the printer body 10 and the movable blade 42 provided on the lid 20 form a cutter to cut the recording paper 100. The movable blade 42 is moved toward the fixed blade 41 by a motor driving force to cut the recording paper 100 between the fixed blade 41 and the movable blade 42.

Furthermore, the printer body 10 is provided with a lock lever 15 for detaching the platen roller 50 pressed against the thermal head 30. By pressing the lock lever 15 downward, the platen roller 50 is separated from the thermal head 30, so that it is possible to disengage the platen roller 50 from the printer body 10. That is, the platen roller 50 is locked by catching a hook 60 formed monolithically with the lock lever 15 on a shaft of the platen roller 50. Furthermore, by pressing the lock lever 15 downward, the hook 60 is lowered to disengage from the shaft of the platen roller 50. As a result, it is possible to detach the platen roller 50 from the printer body 10.

According to the printer of this embodiment, the platen roller 50 is attached to the lid 20. Therefore, by sliding the open lever 21 provided on the lid 20 downward to press the lock lever 15 downward, it is possible to detach the platen roller 50 from the printer body 10 and open the lid 20.

When the platen roller 50 is detached from the printer body 10 by operating the lock lever 15, the platen roller 50 urged by a spring provided in a printer mechanism part is pushed out. Therefore, according to this embodiment, a force due to the spring, that is, a force acting in a direction in which the platen roller 50 is pushed out by the spring, is applied as part of a force to open the lid 20.

In the case of loading the printer according to this embodiment with the recording paper 100, the roll of recording paper 100 is loaded in the body case 11 of the printer body 10, and the lid 20 is closed.

According to an alternative structure of the printer of this embodiment, the platen roller 50 may be provided in the printer body 10 and the thermal head 30 may be provided on the lid 20.

Next, a method of opening the lid 20 according to the printer of this embodiment is described. The lid 20 is opened, for example, when the recording paper 100 in the printer body 10 has run out or in the case of replacing the recording paper 100.

First, the case where the lid 20 is closed is described with reference to FIGS. 2, 4 and 5. FIGS. 4 and 5 are a side view and a cross-sectional view, respectively, of the printer with the lid 20 closed.

The open lever 21 attached to the lid 20 includes a slidable part 21a that slides in the groove 22 formed in the front surface, namely, the exterior surface, of the lid 20 along its lengthwise direction, an operation part 21b that projects

outward from the slidable part 21a to be operated by a human finger or the like, and a projection 21c that projects inward relative to the lid 20. The projection 21c includes an end 21d that contacts the lock lever 15. A spring 23 is connected to the open lever 21. The spring 23 is provided to urge the open lever 21 in a direction to return the open lever 21 pressed downward by a human finger or the like upward. Furthermore, a slope 15a is formed on part of the lock lever 15 provided in the printer body 10 which part contacts the end 21d of the projection 21c of the open lever 21. The lock lever 15 is provided in the printer body 10 to be pivotable about an axis of rotation that lies in the direction going into the plane of FIG. 5.

Next, as depicted in FIGS. 6 through 8, a downward force is applied to the operation part 21b of the open lever 21 with a human finger or the like to move the slidable part 21a downward (in the direction indicated by an arrow in FIG. 8) in the groove 22. FIGS. 6, 7 and 8 are a perspective view, a side view and a cross-sectional view, respectively, of the printer with the slidable part 21a moved downward.

As depicted in FIGS. 6 through 8, the open lever 21 is moved downward by a downward movement of the slidable part 21a in the groove 22. In accordance with this movement of the open lever 21, the projection 21c also moves downward. Therefore, as depicted in FIG. 8, the end 21d of the projection 21c of the open lever 21 depresses the lock lever 15 while moving along the slope 15a of the lock lever 15.

Next, as depicted in FIGS. 9 through 11, a downward force is further applied to the operation part 21b of the open lever 21 with a human finger or the like to move the slidable part 21a downward from the position depicted in FIGS. 6 through 8. FIGS. 9, 10 and 11 are a perspective view, a side view and a cross-sectional view, respectively, of the printer with the slidable part 21a moved further downward.

When the slidable part 21a of the open lever 21 moves further downward from the position depicted in FIGS. 6 through 8 in the groove 22, the projection 21c also moves downward to cause the end 21d of the projection 21c to press the lock lever 15 as depicted in FIG. 11. The lock lever 15 is pressed by the end 21d to a particular position to unlock the platen roller 50. When pressed to a predetermined position after the platen roller 50 is unlocked, the lock lever 15 does not move further and remains stationary. At this point, because the left end side of the lock lever 15 in FIG. 11 moves downward, the slope 15a also inclines to the lower left as depicted FIG. 11. In response to the operation of moving the operation part 21b downward, the end 21d of the projection 21c of the open lever 21 slides downward and outward (leftward in FIG. 11) along the slope 15a of the stationary lock lever 15. As a result of this outward movement of the end 21d of the projection 21c of the open lever 21 along the slope 15a of the lock lever 15, a force is applied to the open lever 21 in a direction to open the lid 20, so that the lid 20 pivots about a shaft at the connection to the printer body 10 to open.

According to this embodiment, when the lock lever 15 is depressed to the predetermined position, a force is applied to the platen roller 50 in a direction to move away from the thermal head 30. This force becomes part of a force to open the lid 20.

Thereafter, as depicted in FIGS. 12 through 14, the lid 20 opens. FIGS. 12, 13 and 14 are a perspective view, a side view and a cross-sectional view, respectively, of the printer with the lid 20 open.

When the lid 20 opens, the end 21d of the projection 21c of the open lever 21 is separated from the lock lever 15, so that the lid 20 is completely open. Thereafter, when a human

finger or the like is detached from the operation part 21b of the open lever 21, the open lever 21 is moved upward by the spring 23 to return to its original state.

According to the printer of this embodiment, it is possible to open the lid 20 by operating the open lever 21 without providing a spring for opening the lid 20 at the connection of the printer body 10 and the lid 20. Thus, because a spring for opening the lid 20 is unnecessary, it is possible to reduce the cost of the printer.

As described above, at the time of cutting the recording paper 100, the movable blade 42 slides toward the fixed blade 41. FIGS. 15 through 18 are diagrams illustrating the cutting of recording paper with a fixed blade and a movable blade according to this embodiment. The movable blade 42 is moved via gears 44 and 45 by rotating the motor 14 to slide from the position depicted in FIG. 15 to the position depicted in FIG. 16. By thus sliding the movable blade 42 toward the fixed blade 41, the recording paper 100 is cut by the fixed blade 41 and the movable blade 42. After cutting the recording paper 100, the movable blade 42 moves with the urging force of a movable blade spring 43 connected to the movable blade 42 to return to the original state as depicted in FIG. 15.

At the time of cutting the recording paper 100, however, the recording paper 100 may be stuck between the movable blade 42 and the fixed blade 41 as depicted in FIG. 17 to prevent the movable blade 42 from returning with the force of the movable blade spring 43. In this state, because it is not possible to move the lock lever 15 by operating the open lever 21 provided on the lid 20, it is not possible to open the lid 20.

In the state where the recording paper 100 is stuck between the fixed blade 41 and the movable blade 42 as in FIG. 17, if it is possible to directly operate the lock lever 15, it is possible to separate the platen roller 50 from the printer body 10. As a result, it is possible to return the movable blade 42 to the original state with the movable blade spring 43 by separating the fixed blade 41 and the movable blade 42 and separating the gears 44 and 45 as depicted in FIG. 18. When the lid 20 is closed, however, it is not possible to operate the lock lever 15 inside the lid 20.

A method of opening the lid 20 with the lock lever 15 is described. According to the printer of this embodiment, it is possible to operate the lock lever 15 even when the lid 20 is closed. The open lever 21, which is formed of a deformable material such as a resin material, is removable from the lid 20. FIG. 19 is a perspective view of the printer with the open lever 21 removed from the lid 20 that is closed, illustrating the case where the recording paper 100 is not loaded in the body case 11.

An opening 20a is formed in a part of the lid 20 from which the open lever 21 is removed. The lock lever 15 is positioned beyond the opening 20a when viewed from outside the lid 20. Therefore, even when the lid 20 is closed, it is possible to disengage the platen roller 50 from the printer body 10 by inserting a driver or the like through the opening 20a of the lid 20 and operating the lock lever 15. As a result, the lid 20 opens to separate the fixed blade 41 and the movable blade 42, so that it is possible to return the movable blade 42 to the original position with the movable blade spring 43.

The above-described process is described in more detail with reference to FIGS. 20 through 24. FIG. 21 and the subsequent drawings may be different in details in part from, for example, FIGS. 1 through 14 and 20 for convenience of depiction, but such differences do not affect the configuration of this embodiment.

First, the open lever 21 attached to the lid 20 as depicted in FIG. 20 is removed from the lid 20 as depicted in FIG. 21. As a result, the opening 20a is left behind in a part of the lid 20 in which the open lever 21 has been provided, so that the lock lever 15 is exposed through the opening 20a. The removed open lever 21 is described in detail below.

Next, a tool such as a driver is inserted through the opening 20a to press the lock lever 15 downward as depicted in FIG. 22. In FIG. 22, a tool is not depicted. As a result, the platen roller 50 is disengaged to slightly open the lid 20 as depicted in FIG. 23. The lid 20 thus slightly opens to release the recording paper 100 stuck between the fixed blade 41 and the movable blade 42, so that the movable blade 42 is moved by the movable blade spring 43 to return to the original state.

As a result of the disengagement of the platen roller 50, it is possible to further open the lid 20 into the state as depicted in FIG. 24, where the lid 20 is completely open.

FIG. 25 is a perspective view of the printer with the open lever 21 removed and the lid 20 completely open, illustrating the case where the recording paper 100 is loaded in the body case 11.

Next, the open lever 21 is described with reference to FIGS. 26 through 28. FIGS. 26(a), 26(b), 26(c), 26(d), 26(e) and 26(f) are a front view, a rear view, a plan view, a bottom view, a left side view and a right side view, respectively, of the open lever 21. FIGS. 27(a), 27(b), 27(c) and 27(d) are front-side perspective views of the open lever 21 taken from upper left, lower left, upper right, and lower right, respectively. FIGS. 28(a), 28(b), 28(c) and 28(d) are rear-side perspective views of the open lever 21 taken from upper left, lower left, upper right, and lower right, respectively.

The open lever 21 has the slidable part 21a and the operation part 21b provided on the front side and has the projection 21c including the end 21d provided on the rear side. Furthermore, two thin plate-shaped connection parts 21e and 21f are provided on the open lever 21 on its rear side to extend in a direction substantially perpendicular to a rear surface of the open lever 21 in order to provide the open lever 21 on the lid 20. The open lever 21 is attached to the lid 20 by inserting the two connection parts 21e and 21f into the opening 20a of the lid 20. To prevent removal of the open lever 21 from the lid 20 when the open lever 21 is operated, a connection projection 21g is provided at an end of the connection part 21e, and a connection projection 21h is provided at an end of the connection part 21f.

FIG. 29 is a diagram illustrating the open lever 21. As depicted in FIG. 29, the connection projections 21g and 21h are shaped to project outward from each other. When the connection parts 21e and 21f are inserted into the opening 20a of the lid 20, the connection projections 21g and 21h move inside the lid 20. As a result, the connection projections 21g and 21h catch an interior surface 20b of the lid 20 at opposite edges of the opening 20a, so that the open lever 21 is attached to the lid 20. The open lever 21 thus attached to the lid 20 is not removed from the lid 20 by being normally operated.

The open lever 21 is formed of a relatively soft resin material or the like, and the two connection parts 21e and 21f, which are formed into a thin plate shape, are flexible and easy to bend. Therefore, while the open lever 21 is not removed by being normally operated, the open lever 21 can be removed from the lid 20 by applying a strong force to the open lever 21.

Furthermore, to facilitate removal of the open lever 21 from the lid 20, a projection slope 21m may be formed on a part of the connection projection 21g that faces the interior

surface 20b of the lid 20, and a projection slope 21n may be formed on a part of the connection projection 21h that faces the interior surface 20b of the lid 20 as depicted in FIG. 30. The projection slope 21m is formed to gradually increase the interval between the interior surface 20b and the connection projection 21g as moving away from the opening 20a in the leftward direction of the drawing. Likewise, the projection slope 21n is formed to gradually increase the interval between the interior surface 20b and the connection projection 21h as moving away from the opening 20a in the rightward direction of the drawing. Accordingly, at the time of removing the open lever 21 from the lid 20, the projection slope 21m of the connection projection 21g and the projection slope 21n of the connection projection 21h contact the opposite edges of the opening 20a during the removal. At this point, the connection parts 21e and 21f flex to gradually reduce their interval. Therefore, it is possible to easily remove the open lever 21 from the lid 20.

Furthermore, to facilitate removal of the open lever 21 from the lid 20, a lid interior slope 20c may be formed on a part of the interior surface 20b of the lid 20 that faces the connection projection 21g of the open lever 21, and a lid interior slope 20d may be formed on a part of the interior surface 20b of the lid 20 that faces the connection projection 21h of the open lever 21, as depicted in FIG. 31. The lid interior slope 20c is formed to gradually increase the interval between the interior surface 20b and the connection projection 21g as approaching the edge of the opening 20a. Likewise, the lid interior slope 20d is formed to gradually increase the interval between the interior surface 20b and the connection projection 21h as approaching the edge of the opening 20a. Accordingly, at the time of removing the open lever 21 from the lid 20, the connection projections 21g and 21h of the open lever 21 contact the lid interior slopes 20c and 20d, respectively, of the lid 20 during the removal. At this point, the connection parts 21e and 21f flex to gradually reduce their interval. Therefore, it is possible to easily remove the open lever 21 from the lid 20.

Furthermore, according to this embodiment, to facilitate removal of the open lever 21 from the lid 20, a recess 21k is formed in the rear surface of the open lever 21 as depicted in FIGS. 26(b), 27(b), 27(d) and 28. When the open lever 21 is attached to the lid 20, the recess 21k formed in the rear surface of the open lever 21 forms a gap between the lid 20 and the open lever 21. By inserting a pointed tool into this gap, it is possible to easily remove the open lever 21 from the lid 20.

It is possible to reattach the removed open lever 21 to the lid 20 by inserting the connection projection 21g of the connection part 21e and the connection projection 21h of the connection part 21f formed on the rear surface of the open lever 21 into the opening 20a of the lid 20.

Furthermore, when a thickness T of the slidable part 21a of the open lever 21 is smaller than a width W of the opening 20a of the lid 20 as depicted in FIG. 32, it is possible to operate the lock lever 15 by inserting the open lever 21 into the opening 20a. Specifically, as depicted in FIG. 33, the lock lever 15 exposed through the opening 20a may be operated with the open lever 21 by inserting the open lever 21 in place of a tool into the opening 20a from which the open lever 21 is removed.

A printer is described above based on an embodiment. The present invention, however, is not limited to the specifically disclosed embodiment, and variations and modifications may be made without departing from the scope of the present invention.

DESCRIPTION OF THE REFERENCE
NUMERALS

- 10** printer body
11 body case (recording paper holder)
12 control circuit board
13 motor
14 motor
15 lock lever
15a slope
20 lid
20a opening
20b interior surface of the lid
20c lid interior slope
20d lid interior slope
21 open lever
21a slidable part
21b operation part
21c projection
21d end

21k recess
21m projection slope
21n projection slope
30 thermal head
41 fixed blade
42 movable blade
50 platen roller
60 hook

The invention claimed is:

- 1.** A printer, comprising:
 a printer body;
 a lid attached to the printer body to be opened and closed;
 a lock configured to lock a platen roller attached to one of
 the printer body and the lid;
 a lock lever configured to unlock the locked platen roller;
 and
 an open lever slidably provided on the lid, the open lever
 including a projection,
 wherein a surface of the lock lever that contacts the
 projection is sloped in a direction in which the lid is
 configured to be opened, and
 the open lever is configured to slide to press the sloped
 surface of the lock lever with the projection to open the
 lid.

- 2.** The printer as claimed in claim **1**, further comprising:
 a spring configured to urge the open lever in a direction
 for the open lever to return to an original state.
3. A printer, comprising:
 a printer body;
 a lid attached to the printer body to be opened and closed;
 a lock lever provided in the printer body and configured
 to separate a platen roller and a recording head, wherein
 the platen roller is attached to the lid with the recording
 head attached to the printer body or the platen roller is
 attached to the printer body with the recording head
 attached to the lid; and
 an open lever slidably attached to the lid and configured
 to slide to operate the lock lever,
 wherein the open lever is removably attached to an
 opening formed in the lid, and
 the lock lever is exposed through the opening from which
 the open lever is removed.
4. The printer as claimed in claim **3**, wherein
 the open lever includes a plurality of connection parts
 inserted into the opening and a plurality of connection
 projections each provided at an end of one of the
 connection parts, and
 each of the connection projections contacts an interior
 edge of the opening with the open lever being attached
 to the lid.
5. The printer as claimed in claim **4**, wherein a projection
 slope is formed on each of the connection projections to
 increase an interval between said each of the connection
 projections and an interior surface of the lid in a direction
 away from the opening.
6. The printer as claimed in claim **4**, wherein a lid interior
 slope is formed on each of parts of an interior surface of the
 lid that face the connection projections to increase an
 interval between each of the connection projections and the
 interior surface of the lid toward the opening.
7. A printer, comprising:
 a printer body;
 a lid attached to the printer body to be opened and closed;
 a lock lever configured to lock the lid to the printer body;
 and
 an open lever slidably attached to the lid and configured
 to slide to operate the lock lever to unlock the lid,
 wherein the open lever is removably attached to an
 opening formed in the lid, and
 the lock lever is exposed through the opening from which
 the open lever is removed.
